UNITED STATES PATENT OFFICE.

RICHARD NAGLE, OF LYNN, MASSACHUSETTS.

LASTING-JACK.

SPECIFICATION forming part of Letters Patent No. 452,146, dated May 12, 1891.

Application filed January 27, 1891. Serial No. 379,266. (No model.)

To all whom it may concern:

Be it known that I, RICHARD NAGLE, of Lynn, in the county of Essex, State of Massachusetts, have invented certain new and useful Improvements in Clamps for Lasting-Jacks, of which the following is a description sufficiently full, clear, and exact to enable any person skilled in the art or science to which said invention appertains to make and 5 use the same, reference being had to the accompanying drawings, forming part of this specification, in which—

Figure 1 is a side elevation of a lasting-jack, showing my improved clamp in position for use, the standard of the jack being represented as broken off; Fig. 2, a vertical transverse section of the same enlarged, taken on line *xx* in Fig. 1; and Figs. 3 and 4, elevations of the clamp-heads detached.

Like letters and figures of reference indicate corresponding parts in the different figures of the drawings.

My invention relates especially to a clamp which is adapted to be adjustably mounted 25 on a lasting-jack head and is designed to clamp or hold the shank portion of a boot or shoe upper onto the sole during the process of lasting; and it consists in certain novel features, hereinafter fully set forth and claimed, 30 the object being to produce a simpler, cheaper, and more effective device of this character than is now in ordinary use.

The nature and operation of the improvement will be readily understood by all conversant with such matters from the following explanation.

In the drawings, A represents the jack considered as a whole, said jack being of the ordinary form and construction, provided with 40 a sliding toe-piece *b* and hinged heel-piece *d*, mounted on a head or bar *g*, fitted to rotate on the standard *h*.

The clamp B consists of a body portion *i*, having an opening *j*, whereby it is fitted to 45 slide longitudinally on the head *g*, and is secured in position thereon by a set-screw *k*. The body *i* is extended laterally at each side, forming ears or lugs *m*, to each of which a vertically-arranged arm *p* is hinged or piv- 50 oted.

A rod *q* is hinged at *r* to one arm *p* and projects through a slot *t* in the opposite arm *p*. The outer end of said rod is screw-threaded at *v*, and a nut *w* is turned thereon. Hinged to said nut there is a lever *y*, provided with 55 a cam-head *z*, which engages the slotted arm *p*, and when depressed into the horizontal position, as shown in Fig. 2, tends to force said arms *p* toward each other.

To the upper end of each arm *p* an eccentric head *15* is pivoted by screws *16* so as to swing on said arm. Said heads are provided with openings *17* for the screws *16*, whereby they may be adjusted vertically on said arms. The upper or free ends of the heads have a 65 flexible guard or padding *18* thereon to prevent them from cutting or injuring the leather.

In the use of my improvement the clamp is adjusted in any desired position on the 70 head *g* by means of its set-screw *k*. The last *C* is disposed on the jack in the usual manner with the upper in position thereon. The clamp-heads *15* are swung from the arms *p*, so that their padded edges *18* shall take on 75 the last in the shank portion at the rear of the ball, as shown in Fig. 1. By depressing the cam-lever *y* the arms *p* are drawn together and the heads *15* forced tightly against the last, gathering and holding the upper in 80 the shank portion, when it may be readily tacked to the sole.

This device avoids the necessity of employing the pinchers to gather the upper in the shank portion and prevents the material from 85 being torn thereby, as frequently happens where pinchers are used.

I preferably employ rubber or similar material for the padding *18* on the heads *15*, as greater friction is imparted thereby on the 90 leather, causing it to be drawn more smoothly and tightly over the instep. The process of lasting is greatly quickened by the use of my clamp, and the danger of longitudinal pull on the upper, whereby the shoe is frequently mis- 95 shapen, is avoided.

Having thus explained my invention, what I claim is—

In a clamp for lasting-jacks, the combination, with the body mounted on the jack- 100

head, arms hinged to the sides of the body, and a lever having a cam-head for pressing said arms simultaneously inward, of eccentric clamp-heads, each provided with a number of openings and having an inwardly-bent upper end covered with a guard or padding of soft rubber, and screws passing outwardly

through said arms and through one of the openings in each head, substantially as described.

RICHARD NAGLE.
